UNITED STATES PATENT OFFICE

148,579

DESIGN FOR AN AUTOMOBILE STATION WAGON

Delmar G. Roos, Toledo, Ohio, assignor to Willys-Overland Motors, Inc., Toledo, Ohio, a corporation of Delaware

Application April 26, 1946, Serial No. 128,961

Term of patent 14 years

(Cl. D14—3)

To all whom it may concern:

Be it known that I, Delmar G. Roos, a citizen of the United States, residing at Toledo, county of Lucas, and State of Ohio, have invented a new, original, and ornamental Design for an Automobile Station Wagon, of which the following is a specification, reference being had to the accompanying drawings, forming part thereof.

In the drawings,

The characteristic features of my design reside in the portions shown by means of full lines in the drawings.

I claim:

The ornamental design for an automobile station wagon, substantially as shown and described.

DELMAR G. ROOS.
